CONDUIT DRIVING MECHANISM

Application filed June 27, 1927. Serial No. 201,764.

My invention relates to improvements in mechanisms employed to drive conduit pipes and the like through the ground by means of compressed air, and to improvements in the 5 method of assembling and operating the same.

In laying rigid conduit or pipe in the ground it is customary to dig a trench of sufficient depth and width in which the conduit can be placed as the joints are made up by 10 means of couplings, the trench being filled in after the conduit is laid. A great deal of such conduit is used in the large cities to carry electrical conductors for street lighting and other purposes, the conduit being buried in 15 side the curb line, beneath the side walk.

Where concrete side walks have been installed prior to laying the conduit, it is necessary to remove the concrete along a row of squares in order to dig the trench. In such 20 instances a considerable saving is effected by removing the concrete only where required to dig a number of spaced and comparatively short trench sections, which are then connected by means of a series of tunnels under 25 the undisturbed sections of the side walk.

Heretofore it has been customary to use a similar method of procedure in laying rigid conduit and pipes under the street in order to connect adjacent trench sections running parallel with the curb. This necessitates removing the paving and digging a number of short 30 trench sections in the street and driving tunnels under the undisturbed sections in much the same manner as that employed for the 35 side walk runs.

Obviously this method is not only expensive, but also seriously interferes with the flow of traffic in the street. Furthermore faults in the replaced paving almost invariably occur over the trench sections.

I am aware that attempts have been made to force such ducts through the earth from one trench section to another by means of powerful mechanical ratchet jacks, but this 45 method is applicable only where the ground is comparatively soft and where the length of the drive is not great.

With the mechanism and method of my invention, however, the conduit or other pipe 50 may be driven through much harder ground

and for much greater distances than has heretofore been practicable. In many instances I have been able to drive a continuous run of conduit pipe through the ground under the street from the end of a trench at the property line on one side into a hole or trench on the other side of a city street of ordinary width without disturbing the paving or interfering with the flow of traffic, and at a fraction of the cost necessitated by the use of 55 the trench-and-tunnel method.

The general object of my invention is to provide an improved method of, and improved means for, driving conduit pipe and the like through undisturbed ground by 60 means of compressed air.

A specific object is to provide improved means for guiding and driving conduit pipe and the like through the ground under street paving and concrete sidewalks without disturbing the same.

An additional object is to provide improved coupling means for joining the lengths of pipe as a necessary element of the mechanism used to drive conduit pipe and 75 the like through undisturbed ground by means of compressed air.

A further object is to provide improved means, as a driving head for conduit pipe and the like whereby the same may be driven 80 through undisturbed ground by means of compressed air.

Other objects of the invention will be apparent from the following description, illustrated in the accompanying drawings and 85 covered by the appended claims.

A preferred embodiment of my invention is illustrated in the drawings, throughout which like reference numerals are used to indicate like parts.

Figure 1 of the drawings is an exploded assembly of important parts of the compressed air operated driving mechanism, said parts being illustrated partly in section and partly in elevation.

Fig. 2 is a drawing of the driving head of the mechanism partly in section and partly in elevation.

Fig. 3 illustrates the forward end of the driven pipe and the type of coupling which is 100

used to make connection to the driving head.

Figure 4 is a combined section and exterior view of the improved coupling of the invention illustrating the method of coupling or joining the lengths of conduit or pipe.

Figure 5 is a plan view of the guide frame and other parts assembled for the driving of a conduit or pipe from a trench at one side, under the paving, into a second trench at the 10 other side of a street.

Figure 6 is a sectional view through a portion of the street and trench and a side elevation of the assembled mechanism.

Referring particularly to Figs. 1 and 5 of 15 the drawings, the driving mechanism consists preferably of a modified Ingersoll-Rand "paving breaker" 7 which is operated by compressed air supplied through an air hose 8 from a suitable source of supply, not shown.

20 The modifications embraced in my invention consist of machining the barrel-like projection of the front head 9 supplied with the standard "paving breaker" so as to reduce its length and diameter to suitable dimensions 25 preparatory to shrinking on a substantial cup-like steel head piece 10, which is further secured in position on front head 9 by welding circumferentially at 11 as indicated in Figs. 5 and 6. This is the only essential 30 change required for the drive element proper. Certain additional elements of the invention are necessary, however, for its successful 35 operation.

35 A steel retaining ring 12 is made a snug fit in end piece 10 and a tool steel anvil disc 13 slightly smaller in diameter is inserted in the aperture of the retaining ring and bears against shoulder 10' of the head piece. 40 A fibre cushion disc 14 of approximately the same diameter as the hammer disc is next inserted in the aperture, after which, with air hose 8 connected to the driver and to the source of compressed air, the driver is ready 45 for the driving operation hereinafter described.

The rearward end of the pipe 15 to be driven is equipped with a driving terminal 16, the threaded cupped end of which is 50 screwed onto the pipe, the smaller solid end being adapted to fit loosely within retaining ring 12 and bear against fibre cushion disc 14 as shown in Fig. 5. The unthreaded skirt of the cupped end is made a tight fit over the pipe in order to maintain the pipe and driving terminal in true axial alignment and to 55 prevent the buckling or breaking of the pipe at or near the end of the threaded portion.

The forward end of the pipe 15 is provided 60 with a suitable driving head which facilitates the opening of the ground as the pipe is driven through. The driving head 17, which I have found to be most satisfactory for this purpose may be constructed from a spirally fluted pipe reamer 18, the shank 18' of which 65 is a tight fit in a centering plug 19 of such

dimensions as to be forced or driven into a short section of extra heavy threaded pipe 20 which forms the shank of the tool. The three pieces of the tool are securely fastened together by circumferential welding at 21 and 21' as clearly illustrated in Fig. 2. The pipe reamer portion 18 of the driving head should then be tempered to the proper degree of hardness, as the welding referred to has a tendency to draw the original temper. This 75 driving head is secured to the end of the pipe by firmly screwing threaded shank 20 into coupling 22 which, in this case, is illustrated as a reducing coupling. I have found it to be practicable to drive several sizes of pipe with 80 a given size of driving head, the necessary connection in each case being made by selecting a strong pipe coupling 22 of such size as to fit both threaded shank 20 and the size of 85 pipe to be driven.

The flutes 18' of driving head 17 are so spiraled that, as the head is driven into the ground, it rotates the pipe about its longitudinal axis in the proper direction to keep the threaded connections screwed firmly together throughout the length of the pipe, and said rotation also assists in preventing the earth from packing about the pipe. This is an important feature of the improvement, as 90 the several impulses transmitted longitudinally of the pipe during the driving operation have a tendency to loosen the threaded joints, which then wear rapidly and fail to 95 transmit the impulses properly to the driving head, whose function it is to open the way 100 for the pipe.

In order to direct the pipe in a true course and to reduce the strain on the operator to a minimum I prefer to make use of a guide frame 23, thrust plates 28, and drive carriage 105 31, which are assembled in a previously prepared trench T as shown in Figs. 5 and 6. The trench is dug to a length of about 14 feet, approximately 2 feet 6 inches wide and to such depth as will enable the conduit pipe 110 to clear the other pipes and obstructions buried under the street.

Guide frame 23 is preferably constructed of two lengths of iron pipe 24 joined in parallel fixed, space relation by means of several U shaped steel straps 25 welded to their outer sides as shown at 25' in Fig. 6. Threaded steel end pieces 26 are welded to the ends of pipes 24, each end piece 26 being adapted to receive a jack screw 27 having an enlarged 115 cylindrical portion 27' provided with through holes 27" in transverse alignment and at right angles to each other. The outer ends of jack screws 27 have semi-spherical ends.

Steel thrust plates 28 are each provided 120 with an aperture 28' of sufficient diameter to pass the driving head and couplings used in connection with the largest size pipe that can be driven by the equipment, the center of the aperture being in horizontal alignment with 125 130

the operating center of the pneumatic driving mechanism. Semi-spherical depressions 28" are provided in the inner surfaces of plates 28 and so placed as to receive the outer ends of jack screws 27. Lugs 29 are preferably welded to thrust plates 28 and have transverse holes adapted to receive shafts 29' on which pulleys 30 rotate freely. Guide frame 23 and thrust plates 28 are secured in the assembled relation shown by means of jack screws 27. These are screwed outward by means of the usual cylindrical bar, not shown, of proper size to enter holes 27", thus forcing the thrust plates firmly against the ends of the trench. The ends of jack screws 27 and depressions 28" in the thrust plates assure the proper positioning of the frame under the most exacting operating conditions.

The driver carriage 31 is preferably built up of two horizontally disposed steel angle pieces 32 so spaced as to allow their inner, downwardly projecting legs to slide freely along the surfaces of guide-frame pipes 24, said pipes thus acting as horizontal guides. A heavy forward steel cross angle 33 is securely welded to guide angles 32 and is provided with a centrally disposed U-shaped notch in its upwardly projecting leg adapted to receive the neck of driving mechanism 7. A downwardly projecting lug 34 having a transverse hole near its lower extremity is welded to the underside at the mid-point of the horizontally disposed leg of cross angle 33. The driver carriage is completed by welding a rearward steel cross bar 35 to guide angles 32. A U-shaped bend in cross bar 35 at its center and the U-shaped notch in the leg of cross angle 33 serve to support and align the driver mechanism 7 axially with the line of travel along which it is desired to drive the pipe.

A flexible steel wire tension cable 36 provided at one end with a terminal thimble 37 is reeved around pulleys 30 and fastened to lug 34 of the driver carriage by means of shackle 38. The other end of the cable is wound upon a suitable windlass, not shown, thus providing a very satisfactory means for forcing carriage 31 and driver mechanism 7 forward against driving terminal 16 during the driving process. I find that the tension cable rigged in this way is one of the important elements contributing to the success of the driving process. It not only reduces the strain on the operator to a minimum, but provides a firm yet slightly resilient means for transmitting the force of the recoil from the driver to the solidly anchored members of the mechanism. The importance of this feature increases with the length of pipe and with the resistance of the ground through which the pipe is driven. Under ordinary conditions it is usually sufficient to reeve cable 36 around only one pulley 30 of each thrust plate 28 as shown in the drawings, but when

a long drive is attempted, or when the ground is unusually hard, it is desirable to reeve the cable around all four of the pulleys, thus reducing considerably the force of the recoil transmitted to the winch and increasing the effectiveness of the blows of the pneumatically operated piston of the driver element.

In carrying out the process, the trench T and hole H are dug and the apparatus assembled as shown in Figs. 5 and 6, but with the pneumatic hammer 7 and carriage 31 slid along guide frame 23 to the rearward extremity of travel. A length of conduit, or other pipe 15, equipped with driving terminal 16 and driving head 17, is placed in position by the operator with the driving head extending centrally through aperture 28' and bearing against the earth at the end of the trench. The carriage and pneumatic hammer, with ring 12, anvil disc 13 and fibre cushion disc 14 in place, are then drawn forward by winding cable 36 around the winch drum by the operator's assistant until the end of driving terminal 16 bears against fibre cushion disc 14 with considerable pressure. Compressed air is then admitted to the pneumatic hammer from air hose 8 by the operator, who opens the throttle valve of the device by grasping handle 39 and forcing throttle lever 40 back into the handle by pressure from the fingers of the hand. The piston of the pneumatic hammer, being reciprocated in the barrel under the pressure of the air, delivers a series of rapidly recurring blows to the anvil block 41 in the usual manner. The force of each blow of the piston is transmitted by anvil block 41 to the end of driver terminal 16 through the intermediary of anvil disc 13 and fibre cushion disc 14, thus continually vibrating and driving the pipe forward into the ground; the inertia of the pneumatic hammer and carriage, and the tension in cable 36 maintaining the effectiveness of the blows in the desired direction.

Because of the rapidity of the blows, the entire length of pipe is maintained in a state of vibration which is transmitted to the surrounding earth, thereby continually agitating the same and preventing it from packing against the pipe, thus greatly increasing the effectiveness of the blows in driving the pipe forward, whereupon anvil disc 13 is soon forced outward from shoulder 10' and anvil block 41 protrudes more and more from the end of front head 9, as shown in Fig. 1, thus continuing the contact with discs 13 and 14 and continuing to transmit the force of the blows delivered by the reciprocating piston. In the meantime the carriage and pneumatic hammer are being forced steadily forward by the operator's assistant, who is stationed at the winch facing the operator in control of the pneumatic hammer.

Anvil disc 13 serves to distribute the force of the blows, received from anvil block 41 of

the driver, uniformly over fibre cushion disc 14, which in turn serves to transmit the force of the blows to driving terminal 16 without undue shock to the mechanism. The fibre cushion disc is gradually disintegrated by the continued impact of the blows, and finally wears so thin that it must be replaced by a new one. This is done by releasing the throttle lever, slackening the wire rope, and 10 withdrawing the carriage and driver. Retaining ring 12 is then easily removed, after which the old flattened and distended fibre disc is easily driven from the ring, which is then replaced in end piece 10. Anvil disc 13 and a new fibre disc 14 are inserted in the retaining ring, and the carriage and driver are again moved up into engagement with driving terminal 16, and the driving process repeated.

20 When pipe 15 has been driven into the ground to nearly its full length, the carriage and driver are withdrawn, driving terminal 16 is removed, and a coupling 42 is screwed securely onto the end of the pipe. The 25 threaded end of a second length of pipe 15' is then screwed into the other end of the coupling, preferably so the ends of the pipes meet at the center, as shown in Fig. 4 of the drawings.

30 The unthreaded skirt portions 42' of the coupling are made a tight fit over pipe sections 15 and 15', which are maintained thereby in true axial alignment. Skirts 42' serve also as reinforcements to prevent the buckling or breaking of the pipes at or near the ends of the threaded portions. Skirts 42' are beveled at 42" to facilitate the passage of the coupling through the ground.

After pipe section 15 is securely connected 40 to pipe section 15', driving terminal 16 is screwed onto the rearward end of the last mentioned section, the carriage and driver are drawn up into engagement with the driving terminal, and the driving is continued as 45 before. In this way, section after section of pipe is added and driven forward until the driving head end is finally forced the required distance into hole H, where driving head 17 is removed. The last section of pipe 50 is usually cut to the proper length, so that it is only necessary to unscrew the driving terminal 16 after removing the balance of the driving equipment in trench T to complete the job. The ends of the pipe projecting into trench T and hole H may then be treated in any way the nature of the job may dictate.

Obviously a run of conduit or pipe may be driven in the opposite direction from trench 60 T by simply reversing the carriage and driver, and reeving cable 36 so as to draw them in the desired direction. In this way pipe runs may be driven from both ends of the trench, and, if desired, the two runs may 65 then be joined to make a continuous run.

Many runs of rigid conduit have been driven under busy streets by means of the equipment and method of my invention through all sorts of ground without having to disturb the paving in any way. In cases 70 where rocks are encountered that are so large that they can not be crowded to one side by the driving head, the vibration of the driving head striking against the obstruction enables the operator or his assistant to accurately 75 locate the obstruction, which may be readily removed through a small hole dug directly over the forward end of the pipe. After the obstruction is removed, the driving process is resumed as before. Where the nature of the obstruction is such that it cannot be removed after the hole mentioned is dug, the carriage 80 31 and driver 7 are removed, after which the pipe may be withdrawn by means of the cable 36, the successive sections being 85 removed by unscrewing at the couplings. Guide frame 23 is then either raised, lowered or moved sidewise in order to assure the pipe's clearing the obstruction, after which it is again driven as previously described.

90 While I have described a preferred form of pneumatic tool as being a pavement breaker of standard construction and have referred to it as a "driver" it will be understood that this tool is one type of a pneumatic or other 95 high frequency percussion hammer and that other types of pneumatic hammer may be used, that will maintain the pipe continually in a state of vibration while being driven.

99 While I have shown and described one specific embodiment of my invention in this specification, it should be understood that various modifications thereof may be made by one skilled in the art, without departing from the spirit of the invention. For example while the cupped head 10 is illustrated and described as affixed to the front head 9 of the pneumatic hammer, it is obvious that the same results would be obtained by affixing the cupped head 10 to the driving terminal 19 instead although experience has proven the arrangement illustrated to be more convenient.

110 Having thus described my invention what I claim as new and desire to secure by Letters 115 Patent is:

1. In a mechanism for driving conduit pipe, a pneumatic driver comprising a standard pneumatic hammer, a cupped front head for said hammer, a retaining ring fitting 120 within and removable from the cupped portion of said head, an anvil disc within said ring engaged with the anvil block of said hammer, a conduit pipe, a driving terminal on the rearward end of said pipe, a cushion disc intermediate of said anvil disc and said driving terminal, and tensioned cable means for feeding said pneumatic driver forward as said pipe is driven.

125 2. In mechanism for driving conduit pipe,

- a standard pneumatic hammer, a cupped front head for said hammer, an anvil disc within said cupped head and engaging the anvil block of said hammer, a conduit pipe, a
5 driving terminal on the rearward end of said pipe, a cushion disc intermediate of said anvil disc and said driving terminal, and tensioned cable means for feeding said pneumatic driver forward as said pipe is driven.
- 10 3. In mechanism for driving conduit pipe, a pneumatic percussion hammer providing a cupped front head, an anvil disc within said cupped head and engaging the anvil block of said hammer, a standard conduit pipe, a
15 driving terminal on the rearward end of said pipe, a cushion disc intermediate of said anvil disc and said driving terminal, and tensioned cable means for feeding said pneumatic hammer forward as said pipe is driven.
- 20 4. In a mechanism for driving conduit pipe, a pneumatic percussion hammer providing a cupped front head, an anvil disc within said cupped head engaging the anvil block of said hammer, a standard conduit
25 pipe, a driving terminal on the rearward end of said pipe, a cushion disc intermediate of said anvil disc and said driving terminal, whereby said hammer may maintain said pipe in a state of vibration transmittable to the
30 surrounding earth to agitate the same and drive said pipe forward coincident with said vibration, and tensioned cable means for feeding said pneumatic hammer formed as said pipe is driven.
- 35 The foregoing specification signed at Seattle, Wash., this 21st day of June 1927.

VAN S. MCKENNY.
